UNITED STATES PATENT OFFICE

EDWARD PFEIFFER, OF NEW YORK, N. Y.

DESIGN FOR A FIGURETTE

Application filed May 23, 1932. Serial No. 43,886. Term of patent 3½ years.

To all whom it may concern:

Be it known that I, EDWARD PFEIFFER, a citizen of the United States, residing at New York, in the county of New York and State of New York, have invented a new, original, and ornamental Design for Figurette, of which the following is a specification, reference being had to the accompanying drawing, forming part thereof.

I claim:—

The ornamental design for a figurette as shown.

EDWARD PFEIFFER.
